(57) **CLAIM**

The ornamental design for a food holder, as shown and
described.

DESCRIPTION

FIG. 1 is a top perspective view of a food holder for
supporting food items on a grill showing our new design;

FIG. 2 is a front elevational view thereof;

FIG. 3 is a right side elevational view thereof, the left side
being a mirror image;

FIG. 4 is a rear elevational view thereof;

FIG. 5 is a top plan view thereof; and,

FIG. 6 is a bottom plan view thereof.
